UNITED STATES PATENT OFFICE.

MORRIS H. AVERY, OF WOONSOCKET, RHODE ISLAND.

CLUTCH.

No. 846,178.

Specification of Letters Patent.

Patented March 5, 1907.

Application filed February 27, 1906. Serial No. 303,220.

To all whom it may concern:

Be it known that I, MORRIS H. AVERY, a citizen of the United States, residing at Woonsocket, in the county of Providence and State of Rhode Island, have invented a new and useful Improvement in Clutches, of which the following is a specification.

This invention has reference to an improvement in clutches, and more particularly to an improvement in the construction of positive friction-clutches or clutch-couplings.

The object of my invention is to improve the construction of a friction-clutch whereby a friction-clutch is produced possessing the driving qualities of a jaw or locking-clutch and capable of being operated with safety at a high rate of speed.

Another object of my invention is to produce a positive friction-clutch that can be positively and instantly released under load with a slight and easy movement of the shipper, thereby making possible the attachment thereto of automatic life-saving devices or mechanisms.

A further object of my invention is to produce a positive clutch without locking-jaws or projections that can be operated to positively drive in one direction and to positively release automatically in the opposite direction, whereby if arranged in series—as, for instance, where several engines or water-wheels drive the same shaft—any one of the motive powers may be instantly stopped or reversed with a positive assurance that the driven power will not be likewise reversed, thereby eliminating the possibility of accidents to the operatives.

A still further object of my invention is to produce a positive friction-clutch in which the clutching parts are brought into perfect alinement before the clutching takes place and when the clutching-surfaces are widely separated, thereby eliminating the possibility of accidental starting.

Still another object of my invention is to produce an efficient and serviceable positive friction-clutch constructed of few parts, thereby reducing the cost of manufacturing the same.

My invention consists in the peculiar and novel construction of a positive friction-clutch having details of construction as will be more fully set forth hereinafter and pointed out in the claims.

Figure 1 is a longitudinal sectional view

taken on line 1 1 of Fig. 2, showing the clutch in the closed position. Fig. 2 is a transverse sectional view taken on line 2 2 of Fig. 1 with the clutch in the closed position. Fig. 3 is a detail view looking at the face of one of the frictional clutching-jaws removed from the clutch, and Fig. 4 is a detail view of the shipper end of the clutch.

In the drawings, *a* indicates a driving-shaft; *b*, a driven shaft; *c*, the driving member of the clutch; *d*, the driven member of the clutch; *e*, the shipping-sleeve; *f*, the shipping-ring; *g*, the shipper; *h h*, the clutching-jaws; *i i*, studs for pivotally supporting the clutching-jaws; *k k*, adjusting-studs on the free ends of the clutching-jaws; *l l*, coiled springs; *m m*, clutching-rolls, and *o* a cam-collar on the driven-shaft *b*.

The driving member *c* of the clutch has the central hub 5, the solid end 6, and the annular flange 7, the inner surface of which forms the clutch-face of the member. This member *c* is secured to the driving-shaft *a* by a feather 8, as shown in broken lines in Fig. 1.

The driven member *d* has the central hub 9 supporting the disk 10 on its inner end, in which are the oppositely-disposed screw-threaded holes 11 11 adjacent its periphery and having the studs 12 12 for the springs *l l*, as shown in Fig. 2. This member *d* is secured to the driven shaft *b* by a feather 13, as shown in broken lines in Fig. 1.

The shipping-sleeve *e* is constructed to have the central hub 14, which has a sliding fit on the hub 9 of the driven member *d*, and the central disk 15, which is adapted to loosely fit and close the open end of the driving member *c* when the clutch is closed. The hub 14 is shaped to have the cone-shaped inner end 16, the intermediate annular ledge 17, the second cone-shaped portion 18, and the annular groove 19 in the outer end of the hub. The disk 15 has the oppositely-disposed holes 20 20 in a position to receive the outer ends of the studs *i i* on the inward movement of the shipping-sleeve. This shipping-sleeve *e* has a longitudinal movement on the hub 9 of the driven member *d* and is prevented from turning on the hub 9 by a spline 21, as shown in Fig. 1.

The shipping-ring *f* is constructed of two semicircular parts shaped to fit in the annular groove 19 in the hub of the shipping-sleeve *e* and is secured together in any well-known way. Each semicircular part of the ring is constructed to have a trunnion 22 and

an outwardly-extending arm 23, in the end of which is a radially-disposed spring-actuated pin 24, held in its normal position in the end of the arm 23 by the tension of the coiled spring 25, as shown in Fig. 1.

The shipper *g* has the transverse slots 26 26 for the trunnions 22 22, the short under beveled side arms 27 27 for depressing the spring-actuated pins 24 24, the end 28, pivotally secured to the bracket 29, which is rigidly secured to the ceiling or any other convenient fixture, and the handle 30 for operating the shipper, as shown in Figs. 1 and 4.

The clutching-jaws *h h* are each constructed to have the convex semicircular clutching-face 31, the transverse hole 32 for pivotally securing the jaw to a stud *i*, the outwardly-turned L-shaped end 33, having the hole 34, and the end boss 35, in which is a radial screw-threaded hole 36 for the adjusting-stud *k*. When the clutching-jaws are in their operative position, a curved wedge-shaped space is formed between the face 31 of the jaw and the circular clutching-face of the driving member *c*, as shown in Fig. 2.

The studs *i i* are firmly secured to the disk 10 of the driven member *d* by screwing the inner ends of the studs into the screw-threaded holes 11 11 in the disk 10, as shown in Fig. 1.

The adjusting-studs *k k* each have the head 37 and the screw-threaded shank 38 adjustably secured in the screw-threaded hole 36 in the boss 35 on the free end of a clutching-jaw *h* by a lock-nut 39, as shown in Fig. 2.

The coiled springs *l l* are each secured at one end to a clutching-jaw *h* and at the other end to a stud 12 on the driven member *d*, as shown in Fig. 2.

The clutching-rolls *m m* are each rotatably secured in a yoke 40, having a stem 41, which extends through the hole 34 in the L-shaped end 33 on the free end of a clutching-jaw *h*. The outer end of the stem 41 is enlarged, and a coiled spring 42 is placed on the stem intermediate the enlarged end and the L-shaped end 33 on the clutching-jaw *h*. The tension of the coiled spring 42 tends to hold the yoke 40 in its normal position against the L-shaped end 33 on the clutching-jaw, as shown in Fig. 3.

The cam-collar *o* has the annular cam edge 43 and is secured to the driven shaft *b* by a set-screw 44 in a position for the radially-disposed spring-actuated pins 24 24 in the shipping-ring *f* to engage with the cam edge 43 of the cam, as shown in Figs. 1 and 4.

In the operation of my improved clutch the clutch is thrown in by moving the shipper *g* toward the clutch. The outer ends of the slots 26 26 in the shipper engaging with the trunnions 22 22 on the shipping-ring *f* move the shipping-ring, and with it the shipping-sleeve *e*, inward or toward the driving member *c*. The cone-shaped end 16 on the

shipping-sleeve engaging with the heads 37 of the adjusting-studs *k k* on the free ends of the clutching-jaws *h h* forces the jaws apart against the tension of the coiled springs *l l* into a position as shown in Fig. 2. The clutching-rolls *m m* now come into frictional contact with the annular clutching-face on the driving member *c*, and the driven member *d* not revolving the rolls will travel forward against the tension of the coiled springs 42 42 until firmly wedged between the semicircular convex clutching-face 31 on the jaws *h h* and the annular clutching-face on the driving member *c*, when positive and simultaneous rotations of the driving and driven members *c* and *d* must take place. The clutching-jaws *h h* are now held in their operative positions by the heads 37 37 of the adjusting-studs *k k* on the jaws engaging with the annular ledge 17 on the shipping-sleeve *e*, as shown in Fig. 2, which hold and automatically lock the clutching-jaws firmly in position. If the load is heavy to pick up and the rolls do not advance and pinch, a further movement of the shipper *g* toward the clutch moves the shipper-sleeve *e* inward until the second cone-shaped portion 18 engages with the studs *k k* on the clutching-jaws *h h*. This tends to force the clutching-jaws still farther apart and forces the pinching action of the rolls. This second cone-shaped portion 18 also obviates the necessity of fine adjustment, so imperatively essential in friction-clutches as heretofore constructed. The clutch (which I will say has been carrying a heavy load and is rigidly and positively in clutch) is easily thrown out by the operator grasping the handle 30 of the shipper *g* and moving the same away from the clutch. The slot 26 in the shipper *g* allows of a predetermined movement of the shipper before the shipper acts on the shipping-sleeve *e*. This movement or lost motion of the shipper is sufficient to allow the under beveled arms 27 27 to engage with and depress the pins 24 24 against the tension of the springs 25 25, thus moving the pins into the path of the cam edge 43 on the revolving cam-collar *o*, which engaging with the pins moves the shipping-ring *f* and the shipping-sleeve *e* outward. This outward movement of the shipping-sleeve *e* releases and allows the clutching-jaws *h h* through the tension of the springs *l l* to return to their normal or inoperative position and the trunnions 22 22 on the shipping-ring *f* to engage with the inner ends of the slots 26 26 in the shipper, thus releasing the pins 24 24 from the arms 27 27 on the shipper *g*, which is now left in a position to throw the clutch in when required.

It is evident that by reversing the position of the clutch on the shafts *a* and *b* the member *d* could be the driven member and that it is also within the scope of this invention to have a positive drive in both directions when

required by suspending from the studs *i i* two clutching-jaws *h h* in a position to bring the free ends of the jaws in opposite positions, with the springs *l l* connected to both 5 jaws, without materially affecting the spirit of my invention.

Having thus described my invention, I claim as new and desire to secure by Letters Patent—

- 10 1. A clutch comprising a driving member having an internal annular clutching-face, a driven member, a plurality of clutching-jaws pivotally secured to the driven member tangentially to the clutching-face on the driving member, rolls rotatably supported on the outer face of the clutching-jaws, coiled springs operatively secured to the clutching-jaws and to the driven member, a sleeve having a cone-shaped inner end adapted to engage with the free ends of the clutching-jaws, means on the clutching-jaws adapted to adjust the jaws relative to the sleeve, means for moving the sleeve inward, whereby the jaws are expanded and the rolls caused to 15 pinch between the clutching-face on the driving member and the outer face of the jaws, and means for moving the sleeve outward, whereby the rolls are instantaneously released.
- 20 2. The combination with a driving-shaft and a driven shaft, of a clutch member secured to the driving-shaft and having an internal annular clutching-face, a clutch member secured to the driven shaft, a plurality of clutching-jaws pivotally secured to the driven member tangentially to the clutching-face on the driving member, rolls rotatably supported under spring tension on the outer 25 face of the clutching-jaws, coiled springs operatively connected to the clutching-jaws and to the driven member, a sleeve having a cone-shaped inner end adapted to engage with the free ends of the clutching-jaws and an annular groove in the outer end, a ring in the annular groove, outwardly-extending arms on the ring, spring-actuated pins in the arms, a shipper operatively connected to the ring, means on the shipper for depressing the spring-actuated pins, and a cam-collar secured to the driven shaft in a position to engage with the spring-actuated pins, whereby on moving the shipper inward the clutching-jaws are expanded and the rolls caused to 30 pinch between the clutching-face on the driving member and the face of the clutching-jaws and on moving the shipper outward the pins are brought into engagement with the cam-collar and the rolls instantaneously released, as described.
- 35 3. In a clutch, a clutching-jaw *h* having the convex semicircular clutching-face *31*, the transverse hole *32* in one end for pivotally securing the jaw to a stud, the L-shaped end *33* having the hole *34*, the boss *35* in which is a screw-threaded hole *36*, the adjusting-stud *k*

having the head *37*, and the screw-threaded shank *38* secured in the hole *36* by a lock-nut *39*, a clutching-roll *m* rotatably secured in the yoke *40* having a stem *41* with an enlarged end which extends through the hole *34* in the *L*-shaped end *33*, and a coiled spring *42* on the stem *41* intermediate the enlarged end of the stem and the *L*-shaped end *33*, as described.

4. In a clutch, a shipper mechanism comprising a shipping-sleeve *e* having a central hub *14* and a disk *15*, the hub *14* having the cone-shaped inner end *16*, the intermediate annular ledge *17*, the second cone-shaped portion *18* and the outer annular groove *19*, the disk *15*, having the oppositely-disposed holes *20 20*, a shipping-ring *f* shaped to fit in the annular groove *19* and having the trunnions *22 22*, the outwardly-extending arms *23 23* in the ends of which are pins *24 24* held under spring tension by the coiled springs *25 25*, a shipper *g* having the transverse slots *26 26*, the under beveled side arms *27 27*, the end *28* pivotally secured to the bracket *29* and the handle *30*, and a cam-collar *o* having the cam edge *43* secured in a position to engage with the pins *24 24*, as described.

5. In a clutch, the combination with a driving-shaft *a* and a driven shaft *b*, of a driving member *c*, a driven member *d*, a shipping-sleeve *e*, a shipping-ring *f*, a shipper *g*, clutching-jaws *h h*, studs *i i* for pivotally supporting the clutching-jaws, adjusting-studs *k k* on the clutching-jaws, coiled springs *l l* connected to the clutching-jaws *h h* and to the driven member *d*, clutching-rolls *m m* rotatably supported on the clutching-jaws and a cam-collar *o* secured to the driven shaft *b*, as shown and described.

6. A clutch comprising a driving member having a clutch-face, a driven member, expandable gripping devices carried by said driven member for engagement with said clutch-face, axially-movable means for actuating said gripping devices in their functions, movable pins carried by said actuating means, automatic means for engagement with said pins to impart initial movement to said actuating means to disengage the same from said gripping devices and manually-operated means for moving said pins to be engaged by said automatic means.

7. A clutch comprising a driving member having a clutch-face, a driven member, expandable gripping devices carried by said driven member and having their bearing-surfaces angularly disposed with relation to said clutch-face whereby a wedge-shaped space occurs therebetween, brackets carried in movable relation by said gripping devices, rolls journaled in said brackets and designed to work in said wedge-shaped space, springs engaging said brackets to normally move the same and the rolls carried thereby toward the larger end of said space, means for expanding

said gripping members and means for restoring said gripping members to initial position upon disengagement of said last-named means.

5 8. A clutch comprising a driving member having a clutch-face, a driven member, movable gripping devices carried by said driven member, a cone-shaped sleeve for engagement with said gripping devices to move the same into frictional contact with said clutch-face, said driven member having laterally-projecting pins, said sleeve having a portion of its material apertured to receive said pins therethrough and means for moving said 15 sleeve axially in either direction.

9. A clutch comprising a driving member, a driven member, gripping devices interposed

therebetween for frictionally binding the same, a movable actuating element for said gripping devices, spring-held pins carried by 20 said element, a cam carried by said driven member for engagement with said pins in one position thereof, and a manual shipper for moving said element, said shipper having an initial free movement or play and including 25 means for actuating said pins in such movement to be engaged by said cam.

In testimony whereof I have signed my name to this specification in the presence of two subscribing witnesses.
